UNITED STATES PATENT OFFICE.

ROGER HARVENGT, OF MONS, BELGIUM.

METHOD OF FISHPLATE CONNECTION OF RAILWAY AND LIKE RAILS.

Application filed March 22, 1924. Serial No. 701,198.

The present invention relates to a novel method of fishplate-connection of railway and like rails, and mainly has for its object to avoid the vibrations which, when the connection of the rails is affected according to the methods at present in use, occur at the passage of the cars over the joints of the rails. With this object in view, according to the present invention, the flat or slightly curved fishplates used heretofore for the connection of the rails are replaced by an improved fishplate element which envelops not only the web of the rail, but also the base of same, so that the rails are supported not only at the bulb but also from underneath and that the ends of the rails are, at the point of connection, completely engaged and incased in the fishplate element, so as to constitute so to speak a solid block with the latter, whereby all vibrations are avoided. The said fishplate element according to the invention is more particularly characterized by the fact that the inner faces of the portions of the said fishplate element covering the upper face of the two wings of the base of the rail are made with two recesses respectively formed in such a manner that the said portions bear on the said wings at two points only of the latter preferably close to the root of the web of the rail.

The portions of the fishplate element which enclose the base of the rail may come right against the longitudinal edges of the wings of the said base.

The invention is, by way of illustration only, shown in the accompanying drawing, which represents a cross section of a rail with a fishplate-element according to the invention in position.

In the said drawing, *a* represents the jaws of the fishplate element and *f* the base or sole-plate thereof, while the above-mentioned recesses are indicated by *g*. As may be seen, these recesses *g* are formed in such a manner that the portions of the fishplate-element which cover the upper faces of the two wings of the base *m* of the rail bear on the said wings at two points *b* only of the latter, the said points being preferably close to the root of the web *n* of the rail.

These recesses render the fishplate-element supple owing to the lever-arms *o*—*p*, so that contact is thus obtained with three portions of the rail, i. e.:

(1) With the lower faces of the bulb of the rail at *h*,

(2) With the two wings at the base of the rail at *b*, and

(3) With the underside of the base of the rail as shown at *i*.

The shape of the recesses may have any desired conformation and by giving said shape a suitable curve it is possible by applying a sufficiently strong pressure to cause the recessed portions forming the lever-arms *o*—*p* to bend so that the points of contact *b* are brought nearer to each other and to the web of the rail, whereby a considerable adjustment may be effected, which is absolutely essential to a good fishplate-connection.

In order to increase the lever-arms *o*—*p* and consequently the extent of the possible adjustment, the width of the upper face of the base or sole-plate *f* of the fishplate-element should preferably exceed the width of the base of the rail as illustrated, but as stated above the portions of the fishplate element which enclose the base of the rail may be in contact at *e* with the longitudinal edges of the base of the rail.

The inner and outer faces of the jaws *a* of the fishplate-element may have any suitable shape, and the more they are curved, the greater will be the extent of the adjustment obtainable by tightening the fishbolts.

Besides the above indicated advantage of eliminating the vibrations occurring at the passage of the cars over the joints the method of fishplate-connection according to the invention offers many other essential advantages which are all derived from the type of the fishplate-element, and of which the most important will be briefly described hereunder:

In an ordinary fishplate-connection comprising two fishplates, the two fishplates necessarily have a tendency to move away from the rail: This tendency is entirely avoided with a one-piece fishplate-element. On the other hand, the elasticity of the fishplate-connection according to the invention, which is in part due to the presence of the recesses *g*, results in the two lateral portions or jaws *a* exerting a constant pressure against the heads and nuts of the bolts, so that the said bolts are firmly locked without any washers being required, and any risk of their becoming loose is avoided.

Another advantage is the following: From a mere inspection of the drawing it will be readily understood that if the fish

bolts are temporarily removed, this will not in any way prevent the normal passage of the trains, so that no suspension of traffic will result from the repair of the permanent way. This point is also extremely important from the point of view of accidents and criminal interference. Indeed, as the fishplate connection will subsist even in the event of accidental rupture of fish-bolts, any 10 risk of the trains being derailed on this account will be avoided. Then, it is well known that with the ordinary method of connection by means of two fishplates, it is sufficient to remove the fishbolts of a few 15 connections to cause a train to be derailed. With the method according to the invention, on the contrary, the intentional withdrawal of a few fish bolts will be of no consequence, and as it is practically impossible 20 for one man to remove single-handed a fishplate-element according to the invention, any danger due to criminal interference such as referred to above will be nonexistent.

Another advantage consists in the rapidity with which the connections can be made owing to the fact that the holes for receiving the same bolt will necessarily be exactly opposite one another, so that no preliminary adjustment to cause the holes in the two 30 jaws of the fishplate-element to register accurately before the bolts can be inserted will be required, hence an important saving of time.

It should be understood that not only the exact position and the conformation of the 35 points of the fishplate-element which have to bear on the wings of the base of the rail, but also in a general manner the inner and outer shape of the fishplate-element, its thickness and its length, may be varied as desired according for instance to the type 40 of the rail and the other requirements of each individual case.

Similarly, the number of fish bolts may 45 vary according to circumstances, for instance according to the weight per foot of rail.

The fishplate-elements may be reinforced or strengthened in any suitable manner, for instance by means of ribs, and at any suitable 50 point; the base or sole-plate of the fishplate-elements may for instance be reinforced in its middle at the point of connection of the rail ends, and the ends may also be reinforced in order better to resist the hammer 55 strokes applied to place the said element in position.

The said fishplate-elements may if considered advisable be thinner at certain portions for instance in order to reduce the 60 weight thereof or to increase the flexibility; thus, if the thickness is reduced at the recessed portions g , the flexibility will be increased so as to allow a greater extent of adjustment by tightening the fishbolts. The 65 fishplate-element may remain unsupported

by a sleeper, but where it rests on a sleeper, the fixing screws used to secure the rail, either directly or indirectly, to the sleepers, may be placed in any suitable manner. For instance, the heads of the said screws may 70 either bear directly on the fishplate-element or partly on a lug formed integrally thereon and partly on the corresponding wing of the base of the rail, or still the fishplate-element may be cut out in places to enable the 75 heads of the aforesaid screws coming in direct contact with the wings of the base of the rail or both with the said wings and with the fishplate-element.

The method of fishplate-connection according to the invention may also be employed to prevent longitudinal displacement of the track, it being sufficient for this purpose to secure fishplate-elements according to the invention firmly to a suitable 80 number of the sleepers.

In the above, reference has been made only to the connection of railway rails, but it is obvious that the fishplate-connection according to the invention may also be applied for connecting the guide-rails of mine shafts, and generally speaking in every case wherein the abutting ends of rails have to be connected, the described method of fishplate-connection being applicable whatever the 95 shape of the rails or their ends may be.

The fishplate-elements according to the invention should preferably be formed in one piece as illustrated, or in such manner as to behave like a one-piece element. 100

In order to reduce the weight a suitable portion of the jaws of the fishplate-element may if desired be cut out, and the said element may also if desired be partially sawn through at suitable points in order to obtain increased flexibility and consequently a greater possibility of adjustments to compensate wear and tear.

The above described method of fishplate-connection is readily applicable for connecting the rails of electric railways, and generally speaking to any electrified track. It is sufficient for this purpose to place the electric connection in any suitable space of the fishplate-elements, for instance in the spaces formed by the hollowed out or recessed portions thereof. The said elements may if desired be formed with spaces or grooves for receiving either the totality of the electric connection or a portion thereof. 110 It is obvious that in view of the rigidity and the fixity of the fishplate-connection according to the invention the electric connections will remain in position. 115

I claim:

1. An improved one-piece fish plate-element, having two facing vertical jaws adapted to support the two underfaces of the bulb and to enclose the web of the rail without contact with the said web, and a 120

base portion forming a supporting sole-plate for the underside of the rail and bent over along its longitudinal edges to cover the upper faces of the two wings of the rail base and connected integrally with the lower edges of the aforesaid vertical jaws, such base and connected integrally with the lower edges of the aforesaid vertical jaws, such bent over portions covering the upper faces of the two wings of the rail base having their inner face formed with a recess so that each will bear on one of the said wings at one point only of the latter situated preferably close to the root of the web of the rail, substantially as described.

2. An improved one-piece fish plate-element having two facing vertical jaws adapted to support the two under faces of the bulb and to enclose the web of the rail without contact with the said web, and a base portion forming a supporting sole-

plate for the under side of the rail and bent over along its longitudinal edges to cover the upper faces of the two wings of the rail base and connect integrally with the lower edges of the aforesaid vertical jaws, such bent over portions covering the upper faces of the two wings of the rail base having their inner face formed with a recess so that each will bear on one of the said wings at one point only of the latter situated preferably close to the root of the web of the rail, the sole-plate of the fish plate-element having a width exceeding that of the base of the rail in such a manner as to increase the lever arm formed by the aforesaid recessed bent over portions.

In testimony whereof I signed hereunto my name.

R. HARVENGT.
